UNITED STATES PATENT OFFICE.

FRANK A. HILL, OF ROCK ISLAND, ILLINOIS.

ENGINE.

1,190,290.

Specification of Letters Patent. Patented July 11, 1916.

Application filed October 31, 1914. Serial No. 869,637.

To all whom it may concern:

Be it known that I, FRANK A. HILL, a citizen of the United States, residing at Rock Island, in the county of Rock Island and State of Illinois, have invented certain new and useful Improvements in Engines; and I do hereby declare the following to be a full, clear, and exact description of the invention, such as will enable others skilled in the art to which it appertains to make and use the same.

This invention relates to engines, and more particularly to those of the internal combustion type.

The invention has for its object to provide means for utilizing the heat of the internal combustion engine in the production of steam to be conveyed to one side of the piston of the engine to increase the power thereof.

With these and other objects in view, the invention consists in the novel construction, arrangement and formation of parts as will be hereinafter specifically described, claimed and illustrated in the accompanying drawing, in which the figure represents a sectional view, partly broken away, through an engine constructed in accordance with this invention.

Referring to the drawing in detail the numeral 5 indicates the cylinder of the engine, which is formed with a plurality of external fins or flanges 6. A piston 7 is reciprocable longitudinally within the cylinder 5 and carries the piston rod 8 slidably mounted through the closed end 9 of the cylinder. The opposite end or head of the cylinder is provided with intake and exhaust ports 10 and 11 respectively adapted to admit combustible gas to the explosion chamber 12 of the cylinder and to permit of the exhaust of the products of combustion. The ports 10 and 11 are controlled by valves 13 and 14 respectively, carrying stems 15 and 16 whereby the valves are mechanically or otherwise operated.

The cylinder 5 is completely inclosed by a substantially cylindrical casing 17 constituting a boiler in the upper portion of which is provided a steam dome 18. The dome 18 is connected with a steam pipe 19 extending through the wall of the boiler 17 and communicating with the cylinder 5 on the side of the piston 7 opposite the explosion chamber 12. The steam admitted to

the chamber 20 of the cylinder 5 is controlled by a mechanically operated valve 21.

The water or other fluid within the boiler 17 is heated by the cylinder 5 and its flanges 6 when the engine is being operated by internal combustion of a suitable fuel. The exhaust port 11 for the explosion chamber 12 is connected with a header 22 in which is secured a plurality of pipes 23 which are coiled about the cylinder in spaced relation to the latter and to the boiler 17 and are connected at their opposite extremities with a pipe 24 extending through the lower portion of the boiler 17 and connecting the pipes 23 with a hollow drum 25 from which the products of combustion pass into the final exhaust pipe 26.

The escape of steam from the chamber 20 is controlled by a valve 27 connecting said chamber with a pipe 28. The lower extremity of the pipe 28 is connected with an approved type of condenser 29, preferably provided with pipes 30 for conducting a relatively cool fluid to the condenser to assist in condensing the steam exhausted during the operation of the engine. The condenser 29 connects with a centrifugal pump 31 by a pipe 32, and by means of said pump the condensed steam is returned to the boiler 17 through a pipe 32. The pump 31 is provided with the usual shaft 33 adapted to be connected with any suitable driving means. The pipe 32 is extended longitudinally through the heating drum 25 and that portion thereof which is disposed within said drum is preferably coiled, as indicated at 34.

In operation, the heat radiating from the cylinder 5, due to the explosion of combustible gases therein, heats the liquid within the boiler 17, thus generating steam or vapor which is conducted to the valve 21 by the pipe 19. It will be understood that the valve 21 is suitably operated so as to open when the piston 7 is adjacent the end 9 of the cylinder and thus cause the piston to be moved toward the head of the cylinder by the pressure of the steam or other vapor. The escape of the steam from the chamber 20 is controlled by the valve 27, the exhaust steam passing downwardly through the pipe 28 and into the condenser 29 where it is condensed or liquefied and conducted to the centrifugal pump 31 through the pipe 32. The pump 31 pumps the liquid from the

condenser 29 back to the boiler 17 through the pipe 32 and coil 34. The heating of the liquid within the boiler 17 is materially assisted by the coiled pipes 23 through which the heated products of combustion from the explosion chamber 12 are conducted to the drum 25. It is also evident that the liquid in returning to the boiler 17 through the pipe 32 is heated by the portions of said pipe exposed to the heated products of combustion passing through the drum 25.

What I claim is:

In a device of the character described, an internal combustion engine including a cylinder having one end closed and an exhaust port at the opposite end, a boiler inclosing said cylinder, a plurality of pipes connected with said exhaust port coiled about said cylinder and extending through

the wall of said boiler, a hollow drum connected with the outer extremities of said pipes, a dome carried by said boiler, a pipe connecting said dome with the closed end of said cylinder, a valve in said pipe, a condenser, a pipe connecting the closed end of said cylinder with said condenser, a pipe connecting said condenser with said boiler and extending through said hollow drum, and a pump connected with the last mentioned pipe for returning the condensed steam to said boiler.

In testimony whereof I affix my signature in presence of two witnesses.

FRANK A. HILL.
